UNITED STATES PATENT OFFICE.

GEORGE E. NEIL, OF CLEVELAND, OHIO.

LAMP.

1,013,947.

Specification of Letters Patent.

Patented Jan. 9, 1912.

Application filed April 3, 1911. Serial No. 618,653.

To all whom it may concern:

Be it known that I, GEORGE E. NEIL, a citizen of the United States, residing at Cleveland, in the county of Cuyahoga and State of Ohio, have invented certain new and useful Improvements in Lamps, of which the following is a specification.

My invention relates to improvements in lamps, and the improvement consists in a lamp, having a cluster of lights for signal and display purposes, all as hereinafter shown and described and more particularly pointed out in the claims.

My improved lamp is more particularly adapted for use on automobiles to signal approaching vehicles when a stop or turn is to be made, and also to display the usual tail light and number plate carried by automobiles according to different laws and regulations now in force.

In the accompanying drawing, Figure 1 is a perspective view of my improved lamp mounted on a bracket supporting a number plate. Fig. 2 is a central vertical section of the lamp. Fig. 3 is a perspective view of the removable interior of the lamp. Fig. 4 is a perspective view of the number-plate and bracket adapted to carry the lamp. Fig. 5 is a front view of the lamp opened to disclose the interior construction.

In detail, the lamp comprises a spun or drawn casing 2 of thin sheet brass formed with a concavo-convex back 3 and provided with annular bead 4 about flared portion 5 of its cylindrical body 6. A flanged cap or cover 7 is hinged at the front of portion 5 to sleeve thereover and abut against bead 4 when shut, and a thumbnut 8 or other device may be used to keep the cover tightly locked. Cover 7 has four openings in its face which contain round glass lenses, designated by 9, 10, 11 and 12, respectively. As arranged, lenses 9 and 10 are in horizontal alinement and lenses 11 and 12 in vertical alinement, all four lenses being grouped or clustered about a common center—the axial center of the lamp including cover 7. Lenses 9 and 10 are preferably clear to shed a white light, whereas lenses 11 and 12 are of different colors, say green and red, respectively. A fifth light is also given off by the lamp through an elongated window comprising a strip of glass or celluloid 14 conforming to circular body 6 and fastened thereto in any preferred mechanical way. This window is at the bottom of body 6 to light up a num-

ber plate 15 which is rigidly secured to bracket 16. This bracket also rigidly supports the lamp in fixed relation centrally above number plate 15 and for this purpose has two vertical rigid stems 17 adapted to sleeve within side lugs 18 of body 6. The face of the lamp and the number plate stand in parallel vertical planes but with the number plate to the rear of bottom light 14 so that it may be illuminated to the best advantage by the downward rays of electric lamp 19, which also illuminates red lens 12, see Fig. 2. The remaining three lenses are independently illuminated by similar electric lamps 19 arranged in focal alinement at the rear thereof, all being removably mounted in suitable electric sockets 20 carried by a disk-shaped diaphragm 21 removably mounted in body 6. Screws 22 passing through openings 23 in diaphragm 21 engage with studs or projections 24 on the inside of back 3 and fasten the diaphragm in place. Each socket and its electric lamp occupies a single compartment obtained by division plates 25 rigidly affixed to the front face of the diaphragm and sub-dividing it into quarters, the sockets and lamps being equi-distant on radial lines and said plates also radiating midway between the same. Furthermore, said division plates 25 project forwardly the full depth of body 6 and conform at their side edges 26 with flaring portion 5 to snugly engage the same when seated therein, and the front edges of plates 25 either abut or come relatively close to the inner face of cover 7 when it is closed or shut. To further guard against the leakage of light from one lamp compartment into another, each lens is surrounded by a ring or flange 30 affixed to the inside of cover 7, and sufficient space is left between the adjacent rings to permit division plates 25 to project therebetween,—an overlapping arrangement permitting a removable cover to be used without admitting light behind any but the selected lenses when the cover is closed.

Diaphragm 21 which supports the separate sockets and lamps is preferably removable to permit wiring of the electrical connections 27 with the sockets, and to permit repairs, and a central outlet 28 is provided in back 3 for the different wires leading to the several sockets. The division walls may be silvered to give a bright reflecting surface, particularly in the compartment be-

hind red lens 12 and above bottom window 14.

To operate the lamp, suitable electric-current and switch connections are made 5 with the electric lamps wherewith the operator may at his election flash the green light above the red to signal "stop"; illuminate the white light at the right of the red and without the green to signal "a turn to the 10 right"; flash the white light at the left of the red to signal "a turn to the left," or illuminate both white lights and the green light above the red light to signal "back up." The red light is constant, as is the white 15 light shed through the bottom window upon the number plate, and in all signaling operations with either the white or green lights the constant red light assumes an important part in indicating to an observer the intent 20 of the operator,—the red light in effect becoming the focusing point for each and every signal.

What I claim is:

1. A lamp body having a front door provided with a cluster of lenses differing in 25 light-transmitting properties, and a removable light support within said body comprising a base plate, division plates at the front thereof, and electric lamp sockets between said plates.

2. A lamp body of cylindrical form having 30 a window in its cylindrical wall, a front door for said body having a cluster of lenses mounted therein, and a light support within said body subdivided into compartments 35 corresponding in number and position to said lenses, one of said compartments being open to said window.

In testimony whereof I affix my signature in presence of two witnesses.

GEORGE E. NEIL.
